ENGINE STARTER CLUTCH

Romeo M. Nardone, Teaneck, N. J., assignor to
 Bendix Aviation Corporation, Teterboro, N. J.,
 a corporation of Delaware

Application October 16, 1944, Serial No. 558,855

7 Claims. (Cl. 123—179)

1

My invention relates to starters and more particularly to engine starters of the type employing an axially shiftable engine-engaging jaw member.

In many engine starters, the engine-engaging jaw member is axially shifted into meshed relation with a similar member by means of an actuator or threaded shaft. The jaw member is usually provided with a transverse wall or section normally disposed and maintained in spaced relation with one end of the actuator by means of a coil spring for yieldably resisting relative movement of the jaw member towards the actuator. In a construction of this character a rod is provided for retaining the jaw member and actuator in operative relationship in order that the driving connection therebetween may not be rendered ineffective due to excessive relative longitudinal movement thereof. The rod slidably extends through the actuator and an opening formed in the transverse wall or section of the jaw member and is provided with a shoulder normally engaging the inner end of the actuator with respect to the jaw member. This rod has a nut threaded on its outer end which abuts the transverse wall of the jaw member and coacts with the shoulder to retain the jaw member and actuator in operative relationship. Also, in a construction of the foregoing described character, one or more washers, which are usually formed of flexible material, are sleeved on the rod and interposed between the end of the spring and the transverse wall to prevent seepage of oil from the crankcase of the engine into the starter through the opening accommodating the rod. Occasionally, in starters of this type, the retaining nut becomes loose due to vibration or faulty assembly and falls into the engine or becomes wedged between the jaw members and damages the various parts and/or precludes proper meshing of the jaw members. Furthermore, when the nut is thus removed from the rod, the washers are displaced from the rod by the actuator thereby permitting oil to seep into the starters. From the foregoing, it will be apparent that the foregoing construction presents many disadvantages and difficulties and necessitates the employment of a relatively large number of parts to accomplish a relatively small number of functions.

One of the objects of my invention is to provide a starter which is so constructed and arranged as to overcome and eliminate the foregoing described disadvantages and difficulties and in a manner not only to require a minimum number of parts or components for accomplishing the results but at the same time materially reduce the number of parts customarily employed for accomplishing various functions.

Another object of my invention is to provide a starter of the foregoing described character

10

wherein the jaw engaging member may be readily removed therefrom or assembled therein without the usual attendant removal or replacement of other parts.

5 An important object of my invention is to provide a starter of the foregoing described character which is simple in construction, durable in use, efficient in operation and economical in manufacture.

With the above and other objects in view, as will hereinafter appear, the invention consists in the combination, and arrangement of parts hereinafter set forth and illustrated in the accompanying drawings, from which the several features of the invention and the advantages attained thereby will be readily understood by those skilled in the art.

Figure 1 is a side elevation of a starter, partly in section, having my invention incorporated therein.

20 Figure 2 is a side elevation of the jaw member.

Figure 3 is a sectional view taken on the line 3—3 of the Figure 2.

Figure 4 is a sectional view taken on the line 4—4 of the Figure 2.

25 Figure 5 is a longitudinal sectional view of an end portion of a modification.

As illustrated in Figures 1 to 4 of the drawings, I provide an engine starter comprising a housing 10 having a pair of cylindrical casing sections 11 and 12 formed with suitable mating flanges 13 and which flanges are detachably connected together and secure the starter to the crankcase of an engine, a portion of the latter being indicated at 14. As is customary, the engine is provided with a crankshaft, the latter or a part connection therewith being equipped with a jaw clutch member 15 whereby the engine is cranked by the starter as hereinafter made apparent. Secured to the section 12 is an electric motor 16 connected to a flange 17 formed on the adjacent end of the section 12 whereby the motor is supported on the housing.

40 The motor 16 may be of any suitable type and has its armature shaft connected to a pair of planetary reduction gear trains 20 and 21 respectively, disposed in the section 12, the casing of the latter being provided with an internal gear track constituting a fixed orbital gear 22 for the trains 20 and 21. The gear train 20 is provided with planet gears 23 disposed between and in mesh with the orbital gear 22 and a sun gear 24 connected to the motor 16 in a suitable manner for driving the train 20. The gears 23 are 45 rotatably mounted on a carrier 25 provided with a hub on which is formed the sun gear 26 of the gear train 21, the latter being provided with planet gears 27, one only of which is illustrated in the drawings. The gears 27 are disposed between and mesh with the orbital and sun gears

22 and 26 and are rotatably mounted on a carrier 28 which constitutes the radial end wall at one end of a drum or barrel 29 which is rotatably mounted, by means of bearing liners 30, within the sections 11 and 12. The wall or carrier 28 is centrally apertured and receives therethrough an elongated hub 31 of a circular drum support plate 32 which is fixed, as by screws 33, to the inside of the wall 28 for rotation with the drum. The hub 31 extends centrally through the trains 20 and 21 and has rotatably mounted thereon the hubs of the gears 24 and 26.

The plate 32 is fashioned with a marginal rib or shoe 34 which engages one end of a clutch pack 35 disposed within the drum 29 and embodying a plurality of friction discs alternately splined to the inner face of the drum and the outer face of an interiorly threaded nut or actuating sleeve 36 of a clutch jaw actuating unit, the sleeve being formed with a flange 37 on which is mounted a ring 38 which engages the opposite end of the clutch pack. Resilient means, in the form of a plurality of coil springs 39, are disposed circumferentially within the drum and are compressed between a pair of spaced retaining members 40 and 41, respectively, the member 40 being mounted on the flange 37. The member 41 is secured to an adjusting nut 42 threaded into the opposite end of the drum 29 and which nut is operable for varying the pressure of the springs, the latter serving to maintain the discs of the clutch pack 35 in engagement to effect simultaneous rotation of the drum 29 and nut 36. Threadedly mounted within the sleeve 36 for rotary and longitudinal movement therein is a screw shaft or actuator 43 which is provided with interiorly disposed and longitudinally extending splines drivably engaging the exteriorly and longitudinally arranged splines formed on an end portion of the tubular shank 45 of a jaw member 46 fashioned with a head 47 having teeth 48. Axial movement of the actuator 43 to the left, as viewed in Figure 1, relative to the sleeve 36 is positively limited by means of a collar 49 integrally formed on the inner end of the actuator 43 and constituting an abutment or stop for engagement with a shoulder 50 formed interiorly and substantially centrally of the sleeve 36.

The head 47 of the jaw member 46 is formed with an inwardly directed rib or collar 51 disposed about and in radially spaced relation to the shank 45 adjacent the head and coacting with the shank to define a seat receiving therein one end of a spring or yielding means 53 disposed about the shank. The opposite end of the spring 53 engages a ring or washer 54 axially slidably mounted on the shank 45 adjacent to the actuator 43. The washer 54, see also Figures 2 and 4, is formed with internal teeth 55 to be slidable along the splines 44 and having inner diameters on and between the teeth slightly in excess of the outside diameter of the shank portion, on which it is mounted, and of the bottoms of the spaces between the splines 44, thereby enabling the washer to be introduced onto the shank and over the splines. A split ring 56 is disposed about the shank 45 between the washer 54 and the ends of the splines 44, and coacts with the ends of the splines to constrain the spring on the shank when the member 46 is removed from the actuator and housing.

Adjacent to the head 47 of the member 46, an oil sealing means 58, Figure 1, is provided for preventing oil from the engine crankcase from

seeping into the housing 10. The means 58 is retained within a recessed portion 59 formed in the end 60 of the section 11 by a retaining plate 61 secured to the end 60 of the section.

5 In operation, assuming the parts to be in the positions illustrated in the drawings, energization of the motor effects operation of the gear trains 20 and 21 with resultant rotation of the drum and sleeve 36. Rotation of the sleeve 36 is translated into an axial shifting of the actuator 43 and which shifting causes the member 46 to move outwardly, through the medium of the spring 53 and washer 54, and engage the member 15. When the members 15 and 46 are thus engaged, cranking of the engine is obtained by continued operation of the motor 16 which supplies sufficient energy for overcoming the static inertia of the engine of which the member 15 is a part. When the engine starts, the member 15 will accelerate beyond the cranking speed of the member 46, and upon deenergization of the motor 16, the member 46 and the actuator 43 will be reversely threaded or shifted back to the jaw-retracted position, by the member 15 in a usual manner.

20 When the motor 16 is energized and the jaw member 46 is shifted towards the jaw member 15 for engagement therewith, should the teeth 48 of the member 46 only partially engage the 30 teeth of the member 15 or abut the radial end faces of the latter teeth, the spring 45 will maintain the teeth 48 in engagement with the member 15 until relative rotation of the members 15 and 46 permits the teeth to properly engage by 35 the action of the spring 45.

35 In the form of the invention depicted in Figure 5, the shoe 34a of the plate 32a engages the adjacent end disc 35a of the clutch pack 35b and embraces a ring 70 which is provided with a flange 71 terminating within the circumferential confines of the end disc 35a. The flange 71 encompasses the adjacent end of the actuating sleeve 36a and is fixed to said sleeve by means of pins, one of which is shown at 72. The discs of the 40 clutch pack 35b are alternately splined to the inner surface of the drum 29a and the outer face of the sleeve 36a, the latter having slidably mounted on its opposite end a compression ring or plate 73 provided with a shoe 74 engaging the adjacent end disc 35c of the pack and coacts with the shoe 34a for maintaining the discs of the pack in engagement to effect simultaneous rotation of the drum 29a and sleeve 36a. Pressure on the plate 73 is applied by springs 39a interposed between the plate 73 and a member 41a, the latter being identical with and functioning in the same manner as the member 41, as effected by the nut 42 of Figure 1. The rings 70 and 73 cooperate to maintain the concentricity of the sleeve 36a while the ring 73 performs the triple function of the flange 37, ring 38 and member 40 of the form of the invention illustrated in Figures 1 to 4 of the drawings, thereby, effecting an economy in manufacture.

65 Although only two embodiments of the invention have been illustrated and described, various changes in the form and relative arrangements of the parts, which will now appear to those skilled in the art, may be made without departing from the scope of the invention. Reference is, therefore, to be had to the appended claims for a definition of the limits of the invention.

What is claimed is:

1. In an engine-engaging jaw member assem-

bly, a jaw member having a head and a shank extending from said head, said shank being provided with lengthwise splines adapted for interfitting engagement with complementary splines carried by a member for effecting rotary and axial movement of said jaw member, a spring sleeved about said shank and engaging said head, retaining means carried on said shank and interposed between said spring and splines, said retaining means adapted to be engaged by said last mentioned member for urging compression of said spring and thus effect axial movement of said jaw member with respect to said member.

2. In an engine-engaging jaw member assembly, a rotatable axially movable member provided with lengthwise splines, a jaw member having a head and a shank extending from said head, said shank being provided with lengthwise splines interfitting said first mentioned splines for effecting rotation and permitting axial movement of said jaw member, a spring sleeved about said shank and engaging said head, retaining means carried on said shank and interposed between said spring and splines, said retaining means being engaged by said movable member for urging compression of said spring and thus effect axial movement of said jaw member with respect to said movable member.

3. In an engine-engaging jaw member assembly, a rotatable axially movable member provided with lengthwise splines, a jaw member having a head and a shank extending from said head, said shank being provided with lengthwise splines interfitting said first mentioned splines for effecting rotation and permitting axial movement of said jaw member, a spring on said shank and engaging said head, an annulus carried on said shank and interposed between said spring and said second mentioned splines, a ring on said shank between said annulus and said first mentioned splines for retaining said spring on said shank, said annulus being engaged by said movable member for urging compression of said spring and thus effect axial movement of said jaw member with respect to said movable member.

4. In a starter construction, an engine-engaging jaw member having a head and a shank extending from said head, a rotatable member, an actuator provided with lengthwise splines and being connected to said rotatable member for rotary movement therewith and axial movement relative thereto, said shank being provided with lengthwise splines interfitting said first mentioned splines for effecting rotation of said jaw member by said actuator, a spring sleeved about said shank and engaging said head, retaining means carried on said shank and interposed between said spring and splines, said retaining means engageable by said actuator for urging compression of said spring and thus effect axial movement of said jaw member with respect to said member.

5. In a starter construction, a clutch pack having a rotatable member, an engine-engaging jaw member having a head and a shank extending from said head, an actuator threaded within said rotatable member for axial movement relative thereto, said actuator being interiorly slotted and receiving said shank, said shank being provided with teeth slidably fitting the slots of said actuator for effecting rotation and permitting axial movement of said jaw member, a spring sleeved about said shank and engaging said head, a retaining member carried on said shank and inter-

posed between said spring and actuator, said retaining member adapted to be engaged by said actuator for urging compression of said spring and thus effect axial movement of said jaw member with respect to said rotatable member, and a ring carried on said shank between said retaining member and said teeth, said ring engaging said teeth and coacting with said head for maintaining said spring and said retaining member on said shank.

6. In an engine engaging clutch jaw member assembly or the like, an axially stationary rotatable nut, a screw shaft adapted for axial movement relative to and rotation with said nut, a clutch member having a clutch portion and a shank extending from said portion, means adapted for cooperation between said shank and said shaft and providing for effecting rotary movement of the clutch member with and axial movement of the clutch member relative to said shaft, spring means disposed about the axis of said shank, and backing means for said spring means including a member axially movable relative to the shank in position between said spring means and said shaft, said backing means member being adapted for operation by said shaft to act through the intermediary of said spring means to effect said axial movement of said clutch member, said backing means retaining said spring means and being retained in position relative to said shank when said clutch member is disassembled from the shaft.

7. In an engine engaging clutch jaw member assembly or the like, an axially stationary rotatable nut, a screw shaft adapted for axial movement relative to and rotation with said nut, a clutch member having a clutch portion and a shank extending from said portion, means adapted for cooperation between said shank and said shaft and providing for effecting rotary movement of the clutch member with and axial movement of the clutch member relative to said shaft, spring means disposed about the axis of said shank, and backing means for said spring means including a member axially movable relative to the shank in position between said spring means and said shaft, said backing means member being adapted for operation by said shaft to act through the intermediary of said spring means to effect said axial movement of said clutch member, and means adapted for position between said backing means member and said first means for retaining said backing means member and said spring means in position relative to the shank when said clutch member is disassembled from the shaft.
